CLAIM

The ornamental design for an alarm with perpetual calendar for traveler, as shown and described.

DESCRIPTION

FIG. 1 is a perspective view of the alarm with perpetual calendar for traveler in a closed state, showing the new design;

FIG. 2 is a front view of the alarm with perpetual calendar for traveler in a closed state;

FIG. 3 is a rear view of the alarm with perpetual calendar for traveler in a closed state;

FIG. 4 is a left side view of the alarm with perpetual calendar for traveler in a closed state;

FIG. 5 is a right side view of the alarm with perpetual calendar for traveler in a closed state;

FIG. 6 is a top view of the alarm with perpetual calendar for traveler in a closed state;

FIG. 7 is a bottom view of the alarm with perpetual calendar for traveler in a closed state;

FIG. 8 is a perspective view of the alarm with perpetual calendar for traveler in an opened state;

FIG. 9 is a front view of the alarm with perpetual calendar for traveler in an opened state;

FIG. 10 is a rear view of the alarm with perpetual calendar for traveler in an opened state;

FIG. 11 is a left side view of the alarm with perpetual calendar for traveler in an opened state;

FIG. 12 is a right side view of the alarm with perpetual calendar for traveler in an opened state;

FIG. 13 is a top view of the alarm with perpetual calendar for traveler in an opened state; and,

FIG. 14 is a bottom view of the alarm with perpetual calendar for traveler in an opened state.
